UNITED STATES PATENT OFFICE.

JOHN H. UHRIG, OF BEVERLY, NEW JERSEY, ASSIGNOR TO UNITED STATES CAST IRON PIPE & FOUNDRY COMPANY, OF BURLINGTON, NEW JERSEY, A CORPORATION OF NEW JERSEY.

CENTRIFUGAL PIPE-CASTING MACHINE AND MOLD.

Application filed November 23, 1926. Serial No. 150,208.

My invention relates to centrifugal pipe casting machines, of the type used in casting De Lavaud pipes, in which a metal (steel) mold rotates in a water jacketed casing, in which casing the water is generally maintained under some pressure and the prime object of my invention is to provide a machine and special construction of mold in which the mold and casing will be so formed that the water will exert substantially no excess pressure on either end of the mold, thus avoiding the tendency of the mold to move longitudinally. By preference, I employ a steel mold, the outer wall of which conforms substantially to the inner conformation of the mold and which is formed without the usual radially extending flanges at the end of the mold, though this feature of my construction forms the subject matter of a separate application, filed November 6, 1926, Serial Number 146,612. By preference also I employ in my construction, as a means for rotating the mold, a driving ring loosely connected to the end of the mold and independently supported, a feature which forms the subject matter of my co-pending application, filed November 23, 1926, Serial Number 150,207.

The nature of my present invention will be best understood as described in connection with the drawings, in which

Figure 1 is a longitudinal section on the angling lines 1—1 of Fig. 2, and

Figure 2 is a cross section on the line 2—2 of Fig. 1.

A indicates the mold, having a bell end A¹ and a spigot end A². A³ indicates the butt end of the bell of the mold, which is formed with a packing groove, indicated at a³, and is interiorly formed to provide a core seat, as indicated at A⁴. A⁵, A⁶ indicate notches formed in the core seat extension of the mold end, in which also are formed key seats, indicated at A⁶, for the use of keys employed to hold the core in position. B indicates a flange secured to the spigot end of the mold by screws indicated at C and having a drum-like extension B¹, in which are formed packing ring seats, indicated at b¹. The diameter of the drum B¹ is, as shown, the same as the outer diameter of the butt end A³ of the mold. D indicates an end ring which is secured to the flange B by screws E, as indicated, or in any other convenient way. F

and F¹ indicate respectively the lower and upper sections of the casing, in which the mold revolves supported on rollers, indicated at O, O. G, G¹ are outer and inner end walls over which the drum B¹ extends and with which, by means of packing rings, indicated at g, it forms a water tight joint. H indicates an end wall at the other end of the water jacket casing, with which, and a part to be described, packing rings h, h form water tight joints. I indicates an end wall at the right hand end of the casing, which is formed with an inwardly extending flange I¹. J, J are shafts supported on the walls H and I and supporting through ball bearings, as shown, rollers, indicated at J¹, upon which rests a driving ring, indicated at K. This driving ring, as shown, is formed with a gear wheel K¹, a shoulder K² and an outwardly extending flange K³, extending around the butt end A³ of the bell end of the mold, with which, by means of the packing k³, it forms a water tight joint. The driving ring is also formed with a downwardly extending flange K⁴, which abuts against the thrust ring L, which rests in turn against the inside of the flange I¹. N is a ring secured to the end of the ring K by bolts, indicated at N¹ and formed with inwardly projecting dogs M¹, which extend into the radial notches A⁵ in the end of the mold. The ring has also an extension M² which rests against the outside of the flange I¹. P is a gear wheel engaged with the gear K¹ and by means of which the ring and mold are rotated.

The essential feature of my invention is to provide means whereby the mold in its assembly with the water jacketed casing will be so constructed that the pressure of the water in the casing will be exerted equally in both directions along the mold, so as to avoid any tendency to move the mold longitudinally. In the construction illustrated, it is obvious that the diameter of the butt end A³ of the mold and the diameter of the drum B¹ being the same, the pressure of the water will be equal at both ends of the mold and there will be no tendency to shift the mold longitudinally.

It will be obvious that my invention is capable of many modifications in form and, except where specifically limited in the claims, I do not wish to be understood as confining myself to the specific construction illustrated,

although it is, I believe, the best form for the utilization of my invention, especially in that it permits of the use of a drum B¹ of minimum diameter.

5 Having now described my invention, what I claim as new and desire to secure by Letters Patent is:

1. In a centrifugal pipe casting machine a casing forming a water jacket surrounding the mold, in combination with a bell ended pipe mold revolvably supported in the casing, and means connected to the bell and spigot ends of the mold forming water tight joints of equal diameter for the water jacket 15 and so as to balance the water pressure and avoid end thrust on the mold.
2. In a centrifugal pipe casting machine a casing forming a water jacket surrounding the mold, in combination with a bell ended pipe mold revolvably supported in the casing, 20

a packing ring fitted to the bell end of the mold forming a water tight joint for the water jacket, a joint forming drum secured to the spigot end of the mold having substantially the same diameter as the part of the bell end to which the packing ring is fitted and a packing ring or rings fitted between said drum and the end wall of the water jacket.

3. A centrifugal metallic pipe mold, the outer wall of which conforms substantially to its inner wall and formed without integral radially extending flanges, said mold having means for forming a water tight joint at its bell end and a separable joint forming 35 drum at its spigot end of substantially the same diameter as the joint formed at its bell end.

JOHN H. UHRIG.
